UNITED STATES PATENT OFFICE.

THOMAS J. LYNCH, OF WATERBURY, CONNECTICUT.

DOOR-STOP.

1,179,201.

Specification of Letters Patent. Patented Apr. 11, 1916.

Application filed November 27, 1915. Serial No. 63,776.

To all whom it may concern:

Be it known that I, THOMAS J. LYNCH, a citizen of the United States, residing at Waterbury, in the county of New Haven and State of Connecticut, have invented new and useful Improvements in Door-Stops, of which the following is a specification.

This invention is an improved door stop or door check, adapted to engage with the floor and either prevent a door from being opened, or to limit the extent to which the door may be opened, the object of the invention being to provide an improved device of this character which may be readily attached to a door, and the floor engaging member of which is normally in inoperative position but may be released and caused to engage the floor and thereby prevent the door from being opened, or limit the extent to which the door may be opened when desired.

The invention consists in the construction, combination, and arrangement of devices, hereinafter fully described and claimed.

In the accompanying drawings:—Figure 1 is an elevation, partly in section of a door stop constructed in accordance with my invention showing the same attached to a door and with the floor engaging member in engaged position in full lines and arranged in inoperative position in dotted lines. Fig. 2 is a horizontal sectional view of the same.

For the purposes of this specification, a portion of a door is indicated at 1 and a floor at 2. In accordance with my invention, I provide a frame or casing 3 which may be made of sheet metal or other suitable material and comprises a back wall 4 and a pair of parallel vertical walls 5.

The floor engaging member 6 is a pawl pivotally mounted as at 7 between the walls 5 of the frame or casing and near the lower outer corners thereof. A spring 7^a is arranged in the frame or casing with its lower end secured as at 8 to the back wall thereof, near the bottom. This spring may be of the form here shown or of any other suitable form. The spring bears against the inner side of the floor engaging member 6 when the latter is in raised inoperative position, and when said floor engaging member is released, the spring serves to turn the floor engaging member outwardly so that by gravity, it drops to and engages the floor and hence serves to secure the door against

being opened or if the door is already partly opened, serves to prevent the door from being opened to a greater extent. I also provide a detent 9 to hold the pawl or floor engaging member normally in inoperative position. The said detent is pivotally mounted as at 10 in the upper portion of the frame or casing at a point near the inner upper corners of the walls 5 and has a depending outer arm 11 to bear on the outer side of the member 6, the weight of the detent serving to cause it to normally hold the member 6 in raised inoperative position. At the lower end of the arm 11 is an out-turned lip 12 which may be readily engaged by the foot so that the detent may be quickly lifted and thus cause the member 6 to be released and thrown outwardly by the spring and engage with the floor to stop or check the door.

By the use of my invention, an intruder may be prevented from entering through a partially opened door and the door may be securely held in closed position or against movement inwardly when in partly opened position.

Having described the invention, what is claimed is:

1. A door stop comprising a frame having a back wall for attachment to a door and a pair of side walls, a floor-engaging member pivotally mounted between the side walls, at a point near the lower ends of said side walls, and a detent pivotally mounted and arranged to bear on the upper ends of the side walls and having a depending outer arm to bear on the outer edges of the side walls and to engage and hold the upper end of the floor-engaging member, when the latter is in raised inoperative position, said detent coacting with the casing to form a housing for the floor-engaging member.

2. A door stop comprising a frame having a back wall for attachment to a door and a pair of side walls, a floor-engaging member pivotally mounted between the side walls, at a point near the lower ends of said side walls, and a detent pivotally mounted and arranged to bear on the upper ends of the side walls and having a depending outer arm to bear on the outer edges of the side walls and to engage and hold the upper end of the floor-engaging member, when the latter is in raised inoperative position, said detent coacting with the casing to form

a housing for the floor-engaging member, and a spring to turn the floor-engaging member outwardly from the casing when the detent is raised and to press the floor engaging member outwardly against the depending arm of the detent, when the floor engaging member is in raised position.

In testimony whereof I affix my signature in presence of two witnesses.

THOMAS J. LYNCH.
